VACUUM CLEANER

Gustaf Einar Lofgren, Riverside, Conn., assignor
to Electrolux Corporation, New York, N. Y., a
corporation of Delaware

Application September 18, 1942, Serial No. 458,792

8 Claims. (Cl. 15—155)

This invention relates to cleaning tools, in particular to a cleaning tool embodying a suction nozzle and adapted for use with a vacuum cleaner of the type comprising a portable suction-separator means to which the tool is connected by a hose.

According to this invention, an improved cleaning tool is provided which, though of general utility, is especially suited for the cleaning of fabrics.

It is an object of the invention to provide a tool of this type that will simultaneously remove both surface litter and deeply imbedded dirt.

It is another object of the invention to provide such a tool having sufficient supporting area over the nozzle opening to prevent the fabric being cleaned from being drawn deeply into the nozzle, thus making it easier to move the nozzle over the surface being cleaned.

A further object of the invention is to provide a nozzle that will produce a substantial amount of suction over the part of the nozzle opening that is covered by the surface being cleaned, even though the remaining portions of the nozzle opening are uncovered.

Still another object of the invention is to provide a tool that is suitable for cleaning in corners and other restricted spaces. To this end it is an object of the invention to provide a tool that effects both deep pile and surface cleaning under the extreme ends of the tool.

A further object of the invention is to provide a passage connecting the inlet opening of a suction nozzle of the above type with the outlet opening thereof that does not have appreciable resistance losses.

Another object of the invention is to provide a cleaning tool that shall be quiet in operation.

A still further object of the invention is to provide a cleaning tool of the above type that has a sufficient length perpendicular to the projection of the nozzle handle on the surface being cleaned to facilitate rapid cleaning over a large area.

Further objects of the invention will become apparent as the description of one mode of attaining the objects of the invention proceeds.

Referring to the drawing forming a part of this specification,

Fig. 1 is a side elevational view showing the improved cleaning tool 12 connected by a hose 11 to a suction-separator unit 10 for producing a flow of air into the tool and exhausting it to the atmosphere after separating out the dirt therein.

Fig. 2 is a front elevational view of the cleaning

tool 12 partly broken away to show the interior thereof;

Fig. 3 is a bottom plan view of the tool;

Fig. 4 is a sectional view taken on the line 4—4 of Fig. 2 with the top portion of the tool indicated in dot-dash lines;

Fig. 5 is a sectional view taken on the line 5—5 of Fig. 2; and

Fig. 6 is a sectional view taken on the line 6—6 of Fig. 2.

Reference will now be made to Figures 2 through 6 and particularly to Fig. 2. There are two main suction openings 13 and 14, one at either end of the nozzle face 33. Connecting these openings is a narrow slot-shaped opening 15. The combined area of these openings is so related to the capacity of the suction-separator unit 10 that a substantial pressure differential (suction) exists between the atmosphere and the space inside the nozzle even when all of the suction openings 13, 14, and 15 are open. Thus, cleaning will be effected over a surface held in contact with a portion of the nozzle face even though the rest of the nozzle face is uncovered.

25 Air entering the suction openings 13, 14, 15 passes through the interior chamber 30 of the nozzle and out through outlet 16 which is connected to the tube 31 forming the hand-grip end of the hose 11. For convenience in handling the

30 axis of the opening 16 must make an acute angle with the plane of the nozzle face 33. In order to make the chamber 30 large enough to reduce air resistance to a minimum without making the chamber roof too high, the bottom wall 34 is extended parallel to the face 33 to a considerable

35 distance back of the nozzle openings 13, 14, and 15. To streamline the chamber 30 in order to reduce the noise produced by air flowing therethrough, there is an air guide comprising a wishbone shaped member 35 having a central fin 36 and two tail fins 37 and 38. These fins divide the chamber 30 into streamlined air passages connecting the suction openings 13, 14, and 15 with the outlet 16.

40 Air may enter the suction opening 15 in one of two ways. It may penetrate deeply into the surface being cleaned, pass under the lip 26 forming the rear wall of opening 15, and enter into the nozzle chamber 30 through the narrow slot 15. As mentioned before, there is always a consider-

45 able pressure differential between the chamber 30 and the atmosphere so that unless a large series resistance opposes the air it will pass under the lip 26 with a high velocity and remove dirt 50 deeply imbedded in the fabric being cleaned.

Since the air passing under lip 26 must pass under a considerable extent of the bottom wall 34, the wall is grooved providing channels 39 through which air may pass freely over the surface being cleaned. Ribs 28 between the grooves space the surface being cleaned from the wall 34 and also provide a gliding surface for the nozzle face.

Air may also enter opening 15 by coming in through opening 17 in the front of the nozzle, over the top wall 18 of channel 19, down through passage 20, under lip 21 and thence into opening 15. Since lip 21 is spaced from the plane of the face 33 of the nozzle, the air passing under the lip does not penetrate deeply into the surface being cleaned but instead, travels over the top of the surface. Since the pressure differential between pressure in passage 20 which is near atmospheric and the pressure in suction opening 15 is nearly the same as the differential between the pressure under wall 34 which is near atmospheric and the pressure in opening 15, the velocity under lip 21 will be higher than that under lip 26 because there is less resistance to air flow over the surface of the rug than through the pile thereof. The high velocity air passing under lip 21 and over the top of the surface being cleaned effects removal of any surface litter that is not removed by the air passing under lip 26.

There is a channel 19 in the face 33 of the nozzle. This channel is in communication at its ends with suction openings 13 and 14. Air may enter the channel 19 in two different ways. First of all, air may pass from the atmosphere deep into the surface being cleaned, under the lip 25 and thence into the channel 19. This effects removal of deeply imbedded dirt similar to the air passing under lip 26. Air may also enter through opening 17, flow over the top wall 18 of the channel 19, down through passage 20, under lip 22 and into channel 19. Lip 22 is spaced from the surface being cleaned just as is lip 21 so that under lip 22 we have high velocity air cleaning the top of the surface being cleaned, just as is done under lip 21.

The lips 21 and 22 are the bottom surfaces of walls defining the passage 20 through the nozzle body. The extent of passage 20 lengthwise across the nozzle face is much less than the extent of channel 19 and suction opening 15 so that there remain at the ends of passage 20 portions 23 and 24 of the nozzle face serving as gliding and supporting surfaces.

It will thus be seen that when the nozzle face is flat against a surface being cleaned, the nozzle in effect comprises an annular suction opening formed by channel 19 and suction openings 13, 14, and 15, having a central opening 20 through the core of the annular suction opening and communicating with the atmosphere. The annular opening has a sealing lip around its outer periphery comprising lips 25 and 26. Air passing under this outer lip must penetrate deeply into the surface being cleaned so as to remove deeply embedded dirt. The annular opening has another lip around its inner periphery comprising lips 21 and 22 and the gliders 23 and 24. This lip communicates with the atmosphere through the central opening 20. Since the lips 21 and 22 are spaced from the nozzle face 33 and hence from the surface being cleaned, air passes under them at a high velocity and removes tenaciously adhering surface litter not removed by the air flowing under the lip around the outer periphery of the annular suction opening.

Since the lips 21 and 22 do not extend to the ends of the nozzle face, they do not effect removal of tenacious surface litter along the entire length of the nozzle. Hence, it is desirable to provide channels 27 and 28 cut across the lip 26 near the ends of the nozzle to permit high velocity air to pass over the top of the surface being cleaned to remove tenacious surface litter at the ends as well as the center of the nozzle face.

10 These grooves also provide in effect nozzle openings in a plane at right angles to the plane of the main nozzle face 33. These suction openings permit cleaning of a surface at right angles to the surface being cleaned by face 33. This is very useful when corners are being cleaned and also when it is necessary to clean in a narrow space in which the nozzle cannot be inserted except endwise.

It will now be apparent why the nozzle will still do an efficient cleaning job even though only a portion of its face is covered. Although there is a relatively large area over the nozzle face between the lips 25 and 26 leaving room for the central opening 20 and the lips 21 and 22 for cleaning surface litter, all of the air must pass through the restricting orifice comprising openings 13, 14, and 15. This reduces the air flow to a point well within the capacity of the suction-separator unit so that it maintains a substantial suction or pressure differential even though the entire nozzle face is exposed. Furthermore, since the widest suction openings 13 and 14 are at the ends of the nozzle, nearly half of the restricting orifice will always be closed as long as one end of the tool is covered. This aids in the cleaning of corners when only one end of the nozzle can be used at a time. It is to be noted that any air leaking into the covered end of the nozzle face without going under a cleaning lip must pass through either channel 19 or suction opening 15. Since suction opening 15 is directly connected to the suction chamber 36, little air will flow transversely thereto. This leaves only channel 19 which has a sufficiently small cross sectional area to permit a substantial suction to be built up under the covered end of the nozzle even though some air travels through channel 19 and into the space between the suction opening on the end of the nozzle and the surface being cleaned. Such laterally flowing air in channel 19 also aids in the removal of surface litter. When the nozzle is used for area cleaning over a curved surface, the ends of the nozzle may not be in sealing engagement with the surface. Although this may reduce the cleaning effected over the lips 22 and 25 by reducing the suction in channel 19, there will still be a substantial suction in opening 15 causing deep dirt removal under lip 26 and removal of tenacious surface litter under lip 21.

60 It should be pointed out that all of the openings in the nozzle face 33 are rather small so that there are no large unsupported areas. This prevents the surface being cleaned from being drawn into the nozzle openings where it might be so firmly held as to be torn by efforts to free it. Also, it makes it easier to move the nozzle over the surface if the material is not drawn up into the nozzle.

Although the nozzle described is of general utility, its characteristics suit it specially for cleaning lighter fabric materials such as curtains, draperies, and clothing, and also for cleaning surfaces having large areas which are curved and having many corners and narrow spaces such as upholstered chairs, mattresses and suitcases.

The nozzle forming the subject of this invention may be assembled in various ways but the method of assembly shown is believed to be advantageous. The nozzle is formed of two parts, an upper and a lower, which are placed together along the line 4—4 of Fig. 1. The section shown in Fig. 4 is taken along the parting line and illustrates the bottom part of the assembly. The parts may be held together by four screws indicated at 40, 41, 42, and 43.

While only one embodiment of my invention has been shown, it is obvious that many modifications therein may be made without departing from the spirit of the invention. For example, the length of the nozzle might be increased in order better to suit the nozzle for cleaning rugs. Also, the angle of the axis of outlet 16 might be changed thereby reducing the backward extent of the bottom wall 34. The width of the lip 25 might be increased at its ends to provide additional gliding surfaces. The channel 19 has been shown as of fairly large width both to provide sufficient room for the flow of air into openings 13 and 14 and also to permit fairly large particles to be picked up. It might be desirable in some cases to reduce the width of this channel.

The spacing of lips 21 and 22 from the nozzle face determines the size of the most limiting orifice in the path of least resistance for airflow into the nozzle and hence determines the suction or pressure differential which the suction-separator unit is able to maintain when the whole nozzle face is covered. By varying this spacing, the suction may thus be varied as desired and of course the velocity under all of the lips, both outside the annular suction opening and inside, will vary as the suction is changed.

It is intended that these Letters Patent shall cover all forms of the invention falling within the scope of the appended claims.

I claim:

1. A suction cleaning tool comprising an elongated hollow nozzle body having an outlet adapted to be connected to a source of suction and an inlet in the face of the nozzle adapted to be presented to a surface to be cleaned, said inlet comprising relatively large channels adjacent to the ends of the nozzle and a long narrow passage between said channels, and means forming a shallow groove in said face communicating at opposite ends with said large channels and extending substantially parallel to said narrow passage.

2. A suction cleaning tool comprising a hollow nozzle body having an annular suction opening adapted to be presented to a surface to be cleaned, inner and outer lips defining the inner and outer peripheral edges of the suction opening, wall means defining a passage from an opening in the top of the nozzle body into the core of the annular opening to provide communication from the atmosphere to the inner lip of the suction opening, gliding surfaces formed inside said annular suction opening to support the nozzle on a surface to be cleaned with the nozzle opening over said surface, said inner lip being spaced above said gliding surface just sufficient distance to cause air entering the nozzle to pass over the top of a surface being cleaned, said outer lip terminating in the plane of the gliding surfaces, and grooves in the ends of the outer lip providing passages across the lip for the flow of air over the top of the surface being cleaned.

3. A suction cleaning tool comprising an elongated hollow nozzle body having a tubular por-

tion with an opening therein adapted to be connected to a source of suction and a face portion with an annular suction opening adapted to be presented to an article to be cleaned, said nozzle body and said suction opening being elongated in a direction perpendicular to the axis of said tubular portion, wall means defining a passage from an opening in the top of the nozzle body to an opening in the center of the nozzle face forming the core of the annular suction opening, inner and outer lips defining the inner and outer peripheral edges of the suction opening, and glider surfaces near the ends of the nozzle body located within said annular suction opening, the outer lip of said suction opening lying in the plane of the glider surfaces and the inner lip of said suction opening lying in a plane spaced slightly above the plane of the gliding surfaces.

4. A suction cleaning tool comprising an elongated hollow nozzle body having a tubular portion with an opening therein adapted to be connected to a source of suction and a face portion with an annular suction opening adapted to be presented to an article to be cleaned, said nozzle body and said suction opening being elongated in a direction perpendicular to the axis of said tubular portion, wall means defining a passage from an opening in the top of the nozzle body to an opening in the center of the nozzle face forming the core of the annular suction opening, inner and outer lips defining the inner and outer peripheral edges of the suction opening, and glider surfaces depending from said nozzle face adapted to support said nozzle over an article to be cleaned with the suction opening over the article, the outer lip of said suction opening lying in the plane of the glider surfaces and the inner lip of said suction opening lying in a plane spaced slightly above the plane of the gliding surfaces,

40 the inner and outer lips defining one side of the elongated suction opening being very close together so as to define a narrow slot, the inner and outer lips defining the other side of the elongated suction opening being spaced sufficiently farther apart to allow for the passage therethrough of particles of fairly large size.

5. In a suction nozzle, a hollow body formed with an elongated cleaning face, said face being formed with a suction opening comprising an elongated narrow slot terminating in larger passages near the ends of the face, lips bounding the front and back of said suction opening, a relatively large surface extending rearwardly from the lip bounding the back of said opening and spaced above the plane of said lip, and parallel ribs depending from said surface to said plane and extending substantially at right angles to said lip.

6. In a suction nozzle, a hollow body formed with an elongated cleaning face, said face being formed with a suction opening comprising an elongated narrow slot terminating in larger passages near the ends of the face, a relatively narrow lip bounding the rear of said slot, a relatively wide lip bounding the front of said slot, and means forming a shallow groove in said face communicating at opposite ends with said larger passages and separated from said slot by said relatively wide lip.

7. In a suction nozzle, a hollow body formed with an elongated cleaning face, said face being formed with a suction opening comprising an elongated narrow slot terminating in larger passages near the ends of the face, a relatively narrow lip bounding the rear of said slot, a relatively

wide lip bounding the front of said slot, means forming a shallow groove in said face communicating at opposite ends with said larger passages and separated from said slot by said relatively wide lip, and means forming a passageway from the atmosphere terminating in the central part of said wide lip.

8. In a suction nozzle, a hollow body formed with an elongated cleaning face, said face being formed with a suction opening comprising an elongated narrow slot terminating in larger passages near the ends of the face, a relatively nar-

row lip bounding the rear of said slot, a relatively wide lip bounding the front of said slot, means forming a shallow groove in said face communicating at opposite ends with said larger passages and separated from said slot by said relatively wide lip, and means forming a passageway from the atmosphere terminating in the central part of said wide lip, the portions of said wide lip which separate said passageway from said slot and said groove extending downwardly a lesser distance than the remainder of said wide lip.

GUSTAF EINAR LOFGREN.
